UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS, &c.

SPECIFICATION forming part of Design No. 22,068, dated December 20, 1892.

Application filed November 22, 1892. Serial No. 452,887. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles of Spoons and other Similar Articles, of which the following is a specification, reference being had to the accompanying drawings, forming a part thereof.

The figure is an upper or front face view of a spoon handle embodying my design.

The leading feature of my design is a special arrangement of the leaves, fruit, and blossoms of the strawberry plant applied to a spoon handle as follows. At the lower portion of the handle adjoining the shank there is represented a twig of the plant bearing

three leaves *a*. Just beyond the leaves is a grouping of the berries in pairs, the largest pair *b* being next to the leaves, the next smaller pair *b'* a little beyond, and the smallest pair *b''* being located at the extreme outer end of the handle. Between the two pairs of berries *b'* and *b''* are a couple of blossoms *c* of the plant. The outer edges of the leaves, fruit, and blossoms impart their irregular outline to the margin of the handle.

What I claim is,

The design for the handles of spoons and other similar articles as herein shown and described.

AUSTIN F. JACKSON.
